CANDY FORMING APPARATUS

Daniel Pearson and Walter H. Ryan, Los Angeles, Calif., assignors to Pearson Candy Company, Inc., Culver City, Calif., a corporation of California
Filed Feb. 27, 1956, Ser. No. 567,833
7 Claims. (Cl. 107—69)

The present invention relates to candy production apparatus, and more particularly to apparatus for automatically forming relatively hard candy into desired shapes.

An object of the invention is to provide improved apparatus for producing relatively hard stick candy.

Another object of the invention is to provide improved apparatus for producing relatively hard striped and twisted stick candy.

A further object of the invention is to provide automatically operable apparatus for continuously and progressively producing striped candy in stick form of the proper size, and for twisting the same.

An additional object of the invention is to provide automatically operable apparatus for continuously and progressively sizing striped candy in stick form, twisting the same, and then cutting the candy to the desired lengths.

Yet another object of the invention is to provide apparatus for synchronously sizing striped candy to the desired cross-sectional dimension and twisting such sized candy.

Still a further object of the invention is to provide improved apparatus for automatically producing candy canes.

Another object of the invention is to provide automatically operable apparatus capable of continuously and progressively sizing stick candy and cutting it to the desired lengths, and then bending the sticks into cane form.

Still another object of the invention is to provide automatically operable apparatus capable of continuously and progressively sizing striped candy in stick form, twisting the same, cutting it to the desired lengths, and bending the severed sticks into cane form.

An added object of the invention is to automatically shape hard candy sticks into canes.

A further object of the invention is to synchronously sever or cut candy sticks to the required length and then form the severed sticks into candy canes.

Yet a further object of the invention is to provide apparatus capable of automatically producing candy canes in a comparatively rapid and economical manner.

Another object of the invention is to provide apparatus for automatically producing striped candy canes at a rapid rate from an initial mass of striped candy.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

FIGURE 1 is a side elevation of an apparatus for producing candy canes;

FIG. 2 is a top plan view of the apparatus disclosed in FIG. 1;

FIG. 3 is an enlarged section taken along the line 3—3 on FIG. 2;

FIG. 4 is a diagrammatic view of the chain conveyor for bending the candy sticks into a cane form;

FIG. 5 is a horizontal section taken generally along the line 5—5 on FIG. 1, disclosing a portion of the drive mechanism for the apparatus;

FIG. 6 is an enlarged cross-section taken along the line 6—6 on FIG. 2;

FIG. 7 is an enlarged side elevation, with parts shown in section, through a portion of the sizer station;

FIG. 8 is a top plan view of the apparatus disclosed in FIG. 7;

FIG. 9 is a section taken along the line 9—9 on FIG. 7;

FIG. 10 is a section taken generally along the line 10—10 on FIG. 9, disclosing and constituting an elevation of the sizer station as seen from the side opposite the side elevation disclosed in FIG. 7;

FIG. 11 is a cross-section taken along the line 11—11 on FIG. 7;

FIG. 12 is an enlarged top plan view, disclosed partly in section, of one of the sizer wheels and the electric heating element therefor;

FIG. 13 is an enlarged side elevation, shown partly in longitudinal section, of the twister station of the apparatus;

FIG. 14 is a top plan view of part of the apparatus disclosed in FIG. 13;

FIG. 15 is a cross-section taken along the line 15—15 on FIG. 13;

FIG. 16 is an elevation of the opposite side of the twister station from the side elevation disclosed in FIG. 13;

FIG. 17 is a sectional view taken along the line 17—17 on FIG. 16;

FIG. 18 is a side elevation of the cutter station and the discharge conveyor leading therefrom;

FIG. 19 is a top plan view of the apparatus disclosed in FIG. 18;

FIG. 20 is an enlarged section taken along the line 20—20 on FIG. 18;

FIG. 21 is a cross-section taken along the line 21—21 on FIG. 20.

The apparatus disclosed in the drawings has been specifically designed to size striped candy to the proper cross-sectional dimension at a sizer station A, the sized striped candy in continuous rod or stick form then passing through a twister station B, where it is given the desired twist, in order that the striped effect will appear in helical fashion on the candy. From the twister station, the candy passes through a cutter station C, where it is severed to the desired length. The severed lengths are then conveyed, by a transfer conveyor D, to a bending or forming station E, where each stick of candy is automatically bent or formed into a cane shape, from where the candy canes are conveyed to another location at the end of the apparatus.

The apparatus is supported on a suitable main frame 10 and also on an auxiliary frame 11. The main frame 10 carries the mechanism for the sizer station A, twister station B and cutter station C, whereas the auxiliary frame 11, which extends substantially at right angles to the path of movement of the candy through the stations A,

B, and C, carries the mechanism constituting the forming station E. Both frames support the transfer conveyor D and the drive for the forming or bending station E.

The sizer station includes a suitable supporting structure 12 mounted on the upper platform 13 of the main frame. Rotatably mounted in the supporting structure are sets of upper and lower sizer wheels or rollers 14, 15 that have generally concave or toroidal peripheral grooves 16 therein (FIG. 11), the upper and lower sizer wheels of a set substantially contacting each other at their peripheries, their concave grooves 16 together forming a substantially circular shape at the point of contact, which will be the cross-sectional shape of the sized candy.

The upper and lower sizer wheels 14, 15 of each set are mounted for rotation about horizontal axes, the sets being longitudinally spaced from each other. Each sizer wheel 14, 15 is secured to a horizontal shaft 17 rotatably mounted in bearings 18 carried by the upper supporting structure or frame 12. The shaft 17 extends outwardly to the other side of the frame 12, where a spur gear 19 is attached thereto, the spur gear 19 secured to the shaft for the upper sizer wheel 14 meshing with a spur gear 19 secured to the shaft 17 of the lower sizer wheel 15, in order that the upper and lower wheels 14, 15 will rotate in opposite directions, to feed the candy S passing through the opposed grooves 16 in a forward direction.

The several sets of sizer wheels are simultaneously rotated at the proper speed by a motor 20 which is suitably supported on a lower platform 21 of the main frame 10 (FIGS. 1 and 5). This motor carries an expandable type of drive pulley 22 over which a belt 23 passes, which also passes over a driven pulley 24 secured to the drive shaft 25 of a gear reducer 26 of the proper transmission ratio. The driven shaft 27 of the gear reducer has a sprocket 28 attached thereto over which a chain 29 passes, which also meshes with a driven sprocket 30 mounted on a horizontal shaft 31 rotatably mounted in bearings 32 suitably supported on the upper platform 13 of the frame 10. This shaft 31 has a bevel pinion 33 attached thereto meshing with a bevel gear 34 attached to one of the sizer shafts, such as the lower shaft 17 that drives a lower sizer wheel 15 (FIGS. 10 and 11). As stated above, the upper and lower shafts 17 are interconnected by means of spur gears 19, the lower spur gear 19, which is secured to the same shaft 17 as the bevel gear 34, meshing with an upper spur gear 19 to rotate the upper shaft 17 and sizer wheel or roller 14. This upper shaft 17 has a pinion 35 fixed thereto meshing with an idler gear 36 suitably supported on the frame 12, which also meshes with another pinion 35 secured to the shaft 19 for the upper sizer wheel 14 of the intermediate set. The shaft for this wheel has a spur gear 19 for the sizer wheel shaft 17 therebelow. The upper, intermediate pinion 35 also meshes with another idler gear 36 that meshes with another pinion 35 fixed to the end sizer wheel shaft 17. The motion of this shaft is transferred to the shaft 17 immediately therebelow through the intermeshing upper and lower spur gears 19.

From the gear arrangement disclosed, it is evident that all of the sizer wheels 14, 15 are simultaneously rotated at the same speed, since all of the intermeshing spur gears 19 are of the same size, which is also true of the pinions 35. The upper sizer wheels 14 of all sets rotate in a counter-clockwise direction, as seen in FIG. 1, whereas the lower wheels 15 rotate in a clockwise direction.

The mass of striped candy is disposed on a suitable counter surface 38 to the rear of the first set of sizer rollers 14, 15. It is manipulated by the hands of an operator, being fed into the opposed grooves 16 of the first set of opposed sizer wheels 14, 15. These wheels reduce the size of the striped candy stick and feed it onto an intermediate guide trough 39 extending between the first set of sizer wheels and the second or intermediate sizer wheels 14, 15, the horizontal trough or guide 39 being mounted on a suitable vertical support 40 carried by the

upper platform 13. The striped candy stick then passes between the intermediate set of sizer wheels 14, 15, the concave surfaces 16 acting upon it to produce a generally cylindrical form of candy stick to a greater extent. The intermediate set of wheels also feeds the candy stick in a forward direction along another intermediate guide or trough 41 carried on a suitable vertical support 42 mounted on the upper platform 13. The candy slides along this intermediate guide 41 into the space between the third set of sizer wheels 14, 15, which gives it a final sizing and assures that the candy mass has been reduced to the desired cross-sectional dimension.

The candy being fed into the sizer station A is in a semi-plastic condition. To insure its retention in such condition, the sizer wheels 14, 15 are preferably electrically heated. As disclosed most clearly in FIGS. 7, 8, 11 and 12, each sizer wheel has a suitable electrical heating element 43 contacting a side face of the wheel. One terminal of the heating element is connected through a suitable lead 44 to a slip ring 45 mounted upon an insulated disc 46 rotatable with the sizer wheel shaft 17, the other terminal of the heating element being connected to a lead 47 running to another and separate slip ring 48 mounted on the insulated disc 46. Spring-like electric contacting strips or brushes 49 engage the slip rings 45, 48, current being fed from a suitable source (not shown) through suitable leads (not shown) to the slip rings, and from the slip rings to the heating element 43. The sizer wheels 14, 15 are thereby heated, to insure the maintenance of the continuous stick or rod of candy in a semi-plastic and workable state during its passage through the sizer station A.

Although three sets of sizer wheels or rollers 14, 15 have been disclosed, it is evident that a lesser or greater number of sets can be used, as desired.

From the forward set of sizer wheels 14, 15, the formed striped candy passes along a short horizontal guide section or trough 50 into a tubular shaft 51 rotatably mounted in a bearing 52 fixed to the sizer frame of the machine, this tubular shaft constituting the entry portion of the twister station B. This guide tube extends into a carrier 53 for a pair of opposed twister wheels or rollers 54, 55 that are shaped substantially like the sizer wheels, the forward end of the guide tube or shaft 51 having opposed curved portions 56 to conform to the peripheries of the twister wheels (see FIGS. 13 to 17, particularly). The candy passes through the opposed grooves 57 in the twister wheels and into a forward guide tube 58 secured to the carrier 53, which is rotatably mounted in a suitable bearing 59 carried by a standard 60 attached to the upper platform 13 of the frame 10. The rearward end of the guide tube 58 also has oppositely curved portions 61 conforming to the peripheries of the twister rollers or wheels 54, 55.

The twister rollers or wheels 54, 55 are rotated in opposite directions about their own axes to feed the length of striped candy in a forward direction through the guide tubes 51, 58. They are also revolved about the horizontal axis of the guide tubes at a certain speed in relation to the linear feed of the candy therebetween, to give the candy a predetermined twist, and thereby cause the candy stripes to provide a helical or twisted representation with a comparatively large pitch.

To accomplish the simultaneous rotation of the twister rollers 54, 55 about their respective axes, as well as their revolution about the horizontal axis of the guide tubes 51, 58, and of the candy passing therebetween, the carrier 53 is rotated, as well as the rollers 54, 55, at a speed corresponding to the feed rate of the sizer rollers 14, 15 and in synchronization with the latter. Thus, the drive for the carrier 53 and the twister rollers 54, 55 emanates from the same source as the drive for the sizer wheels 14, 15 of the sizer station A. As specifically disclosed (FIGS. 8 to 16, particularly), a pinion 62 is mounted on and fixed to the shaft 31 to which the sprocket 30 is secured, and thereby derives its motion

from the same motor 20 or power source as the gearing and wheels of the sizer station. This pinion 62 meshes with an idler gear 63 suitably rotatably mounted on the sizer station frame 12, this idler gear, in turn, meshing with a gear 64 attached to the hollow shaft or guide tube 51 to which the carrier 53 is secured. Accordingly, the carrier 53 is rotated by means of the gearing about the horizontal axis of the guide tubes 51, 58, the gear 64 attached thereto constituting a driven sun gear. The guide tube and hollow shaft 51 extends through a supporting standard 65 suitably secured to the upper platform 13 of the apparatus, which carries a stationary sun gear 66 suitably secured thereto, as by means of screws 67. Meshing with the stationary sun gear 66 is a planet gear 68 rotatably mounted on the carrier 53 and attached to another planet pinion 69 meshing with another planet gear 70, which is secured to a shaft 71 rotatably mounted in the twister carrier 53. This shaft has a bevel pinion 72 fixed thereto meshing with a bevel gear 73 secured to a shaft 74 carrying one of the twister wheels 55. The shaft 74 of the twister wheel 55 has a spur gear 75 attached thereto meshing with another spur gear 76 fixed to the shaft 77 to which the other twister wheel 54 is secured. The rotating gear mass predominantly on one side of the carrier 53 is counterbalanced by weights 78 on its other side, suitably secured to the carrier, as by the screws 79.

It is apparent that the carrier 53 is rotated directly from the motor 20 through the belt and pulleys 23, 22, 24, transmission gear reducer 26, chain and sprockets 29, 28, 30, pinion 62, idler gear 63, and sun gear 64, to revolve the twister wheels 54, 55 about the horizontal axis of the guide tubes 51, 58. Such revolution of the carrier 53 causes the planet pinion 68 to roll around the stationary sun gear 66, to rotate the planet pinion about its axis, which rotation will be transferred through the planet gear 69 attached thereto to the planet gear 70 attached to the shaft 71 on which the bevel pinion 72 is mounted, the motion of the latter being transmitted through the bevel gear 73 to one of the twister wheels 55, to rotate it about its own axis, the intermeshing spur gears 75, 76 causing simultaneous rotation of the other twister wheel 54 about its own axis and in the opposite direction, to feed the candy passing therebetween in a forward direction. While such forwarding feeding action is occurring, the revolving of the twister wheels 54, 55 will cause them to impart a twist to the candy, by virtue of their frictional contact therewith, the twisting being due to the fact that the rearward portion of the candy, as the portion of the candy held between the last set of sizer wheels 14, 15, is prevented from turning.

From the twister station B, the twisted, striped candy passes along the horizontal guide trough 80, suitably supported on a standard 81 attached to the upper platform 13, to the cutter station C, where the candy is severed into sticks of the desired length. The candy passes between a pair of opposed upper and lower rotatable cutter members 82, 83 (FIGS. 18 to 21, particularly) which are secured to shafts 84, 85 rotatably mounted in a supporting frame 86 mounted on the upper platform 13. The cutters are rotatable in opposite directions by virtue of intermeshing spur gearing 87, 88, each gear being attached to a cutter shaft.

One of the cutter shafts 84 is rotated by a suitable drive motor 89 (FIGS. 1, 2 and 5) that has a drive pulley 90 attached to its shaft 91, over which a belt 92 passes, the belt also passing over a driven pulley 93, that may be of the expansible, variable speed type, connected to the drive shaft 94 of a gear reducer 95, the driven shaft 96 of which has a sprocket 97 secured thereto. A chain 98 passes over this sprocket and also over a driven sprocket 99 secured to one of the cutter shafts 84. It is evident that the rotation of the motor 89 in the proper direction is transmitted through the belt and pulley transmission 90, 92, 93, and the gear reducer 95 to the drive

sprocket 97, from where the motion passes through the chain 98 to the driven sprocket 99 and the upper cutter 82, to rotate the same in the proper direction, which will preferably be in a counter-clockwise direction as disclosed in FIG. 1. At the same time, the lower cutter member 83 is rotated in a clockwise direction because of the intermeshing spur gearing 87, 88.

The cutter members 82, 83 each has a cutter blade 100 mounted on its periphery, as by means of screws 101, the blades preferably being disposed at an angle, with the upper blade 100 inclined in the opposite direction from the lower blade 100, but to the same angular extent. The blades 100 are located on the cutter members 82, 83 so that they are opposite and aligned with each other, and will almost contact, when placed in confronting relation at the point of severing the candy passing therebetween. Thus, as the candy moves between the cutters 82, 83, the severing action will only occur when the upper blade 100 penetrates the upper portion of the candy simultaneously with penetration of the lower portion of the candy by the lower blade 100. The blades 100 are rotated at a proper speed with respect to the rod of candy passing therebetween, as to sever the candy at intervals and to the desired length.

25 The striped and twisted candy passes between the cutters 82, 83 and onto a transfer conveyor D which is constantly rotating and at a comparatively rapid speed, for the purpose of conveying the severed candy sticks to the forming station E. The transfer conveyor (FIGS. 30 1, 2, 18 and 19) includes a horizontally disposed belt 102 which passes over a rearward pulley 103 located immediately in advance of the cutter station C and over a forward pulley or roller 104 at the forming or bending station E. The forward pulley is suitably rotatably supported by the auxiliary frame 11, while the rearward pulley 103 is rotatably carried by the cutter frame 86.

The belt conveyor 102 is rotated by an electric motor 105, the shaft 106 of which has a driving sprocket 107 attached thereto, over which a transmission chain 108 extends, the chain also passing over a driven sprocket 109 secured to a shaft 110 secured to the rear conveyor pulley or roller 103. The upper run of the conveyor belt 102 moves in a forward direction, and will shift each severed length of twisted candy rapidly onto the counter surface 111 of the forming station E, the counter surface extending substantially at right angles to the direction of travel of the conveyor belt. The forward end of each length of candy S is driven against a stop member 112, which is secured, as by bolts or screws 113, 114 to the horizontally disposed counter 115 of the forming station. The stop member 112 can be adjusted, as by having one of the screws 114 pass through a transverse slot 116 in the horizontal flange 117 of the stop member, which will permit shifting of the stop member about the axis of the other screw 113 to a desired position, after which the screw 114 passing through the slot can be tightened, to clamp the stop member 112 against the counter 115.

In order to prevent the candy S from striking the stop member 112 and then bouncing back, or from being deflected upwardly, each severed candy stick S is caused to pass under a retarding brake 120 at the discharge end of the conveyor belt 102. This brake structure 120 includes a bracket 121 suitably secured to the auxiliary frame 11, there being an upper plate 122 fixed to the bracket. A brake arm 123 is pivotally mounted on the support or bracket 121, as by means of a screw or pin 124, the brake arm terminating in a brake shoe 125 urged in a downward direction by a helical spring 126, which engages the shoe and the upper plate or spring seat 122. The shoe 125 can only move downwardly to a limited extent, and will normally be spaced from the conveyor belt 102 a distance that is slightly less than the diameter or vertical height of the candy stick S.

As the candy stick S is moved by the conveyor belt 102 under the shoe 125, the latter frictionally engages the

stick and will prevent it from moving upwardly upon striking the stop member 112, or bouncing in a rearward direction as a result of striking the latter.

When the severed candy stick S arrives at the cane forming station E, its forward portion rests upon the two spaced apart sides 130 of the horizontal counter 115 which is suitably mounted on the auxiliary frame 11. The separated sides 130 define a slot 131 therebetween to permit passage of a chain conveyor 132 having forming dogs 133 attached to the chain links 134 (FIGS. 3 and 4). Fixed to the spaced sides 130 of counter 115 are opposed guide rails 135 which may be of angle form, with their horizontal flanges 136 resting upon and attached to the counter by screws 137, and with their vertical flanges 138 spaced apart a distance substantially equal to the width of a formed candy cane S. The portions 139, 139a of the guide rails or flanges 138 adjacent the stop member 112 are curved in an outward direction, to form an entry space 140 between the guide rails for each twisted candy stick S, which is still in a somewhat plastic and pliant state.

The forming action occurs as a result of the conveyor 132 and its dogs 133 engaging the candy stick S and then moving it against the curved ends 139, 139a of the guide rails 138. Such action will bend the forward portion of the stick S around the outer curved end 139a of one guide rail 138, and the rearward portion of the stick around the opposite curved portion 139 of the rail, to produce the cane shape. The conveyor dogs 133 continue moving between and along the rails 138, causing the handle portion H of the candy cane to be formed, with its short depending portion P generally parallel to the rails 139, the leg portion L of the cane also being formed generally parallel to the rail, as disclosed in FIG. 2.

The chain conveyor 132 for forcing each stick S between the guide rails 138 to produce the candy cane, and for then conveying it between the guide rails to a point of discharge from the apparatus, includes an endless chain 132 passing over a driving sprocket 150 at one end of the counter 115 and a driven sprocket 151 at the other end of the counter. This chain has spaced sets 152 of forming dogs 133 secured thereto, such as disclosed most clearly in FIGS. 2, 3 and 4. Each set 152 includes individual dogs 133 that are connected by pins 153 to the upwardly extending portions 154 of opposed sets of links 134, the dogs 133 of each set being closely adjacent each other when traveling horizontally, but being capable of having their outer portions separate when the chain passes over one of the sprockets (right portion of FIG. 4). The chain 132 itself does not extend above the upper surface 111 of the counter members 130, but the dogs 133 project upwardly a sufficient distance above the counter 115, as well as above the candy sticks S, to insure that the dogs will engage the latter.

Each set 152 of dogs is of a length to substantially conform to the length of the final candy cane S. The sets of dogs are spaced from one another by a sufficient extent to permit the transfer conveyor D to shift a severed, twisted stick into engagement with the stop 112, after a preceding set of dogs and formed candy cane have been removed from the region of the stop, and before the next set of dogs will arrive at the location of the straight candy stick engaging the stop.

The conveyor chain 132 is operated in synchronism with the cutters 82, 83, which will insure appropriate transfer of a straight stick S to the forming station E and against the stop member 112, and the movement of the conveyor chain 132 and the dogs 133 attached thereto against each stick, to form the cane S and convey the formed cane between the opposed guides 139. The dogs 133 also form a lengthwise guide or support for the candy cane S (as is clear from FIG. 2), to insure the straight disposition of its leg portion L and also of its terminal handle portion P. To effect the synchronous drive, the driven shaft 96 of the gear reducer 95, to which the drive sprocket 97 for

the cutters is secured, has a bevel pinion 160 attached thereto meshing with a bevel gear 161 secured to a shaft 162 rotatably mounted in bearings 163 carried by the lower platform 21 of the main frame 10 and by the auxiliary frame 11. A drive sprocket 164 is secured to this counter shaft 162, there being a chain 165 passing over this sprocket and also over a driven sprocket 166 secured to the shaft 167 on which the drive sprocket 150 of the chain conveyor 132 has been fixed, this shaft being suitably rotatably mounted in spaced bearings 168 carried by the auxiliary frame 11.

The drive motor 89 operates through the belt and pulleys 92, 90, 93, gear reducer 95, chain 98 and sprockets 97, 99 to rotate the cutters 82, 83 at a certain speed, to sever the candy S into the proper lengths. At the same time, the same drive mechanism is driving the conveyor 132, the dogs 133 of the conveyor being appropriately located with respect to the cutter blades 82, 83, in order that a candy stick, when severed, will be transferred by the transfer belt 102 very rapidly against the stop 112, and in a position where it can immediately thereafter be engaged by a set 152 of dogs 133 and forced between the curved guide rails 139, 139a into the cane form, the formed cane then being moved fully within the opposed guides 138 to assume the shape disclosed in FIG. 2.

To insure the flat position of the candy cane upon the counter 115 as it is being formed, the terminal portion P of the handle H of the cane is caused to pass under a roller 170 (FIGS. 2 and 3) rotatably mounted in a suitable support 171 mounted on the counter 115 and overlying the path of the terminal portion P of the handle. If such terminal portion P of the handle H tends to be deflected upwardly, then its movement under the roller 170 will cause it to be shifted back down against the surface of counter 115.

In the operation of the entire apparatus, a mass of striped candy is disposed to the rear of the sizer station A. The forward portion of this mass will have been reduced in size by an operator for insertion between the first set of sizer rollers 14, 15 which are being rotated at the proper speed by the drive mechanism. The sizer rollers 14, 15 form the semi-plastic candy mass to the desired rod shape as the latter is passed between the opposed rollers or wheels of each set, the sizer rollers also carrying the formed candy in the forward direction into the twister station B, where they will be continuously fed in a forward direction by the twister rollers 54, 55, the latter being driven by the planetary gearing, while the carrier 53 revolves the twister rollers to impart the appropriate twist to the candy. Such appropriate twist is assured in view of the synchronous rotation of the carrier 53 and of the twister rollers 54, 55 with respect to the feed of the candy by the sizer rollers or wheels 14, 15.

From the twister station B, the continuous length of twisted, striped candy passes between the cutter members 82, 83, which are rotating at a proper speed with respect to the linear speed of the candy, to sever the latter into lengths. When severed, most of the severed candy stick has been transferred onto the conveyor belt 102, which travels at a much faster speed than the linear speed of the sized candy through the sizer and twister stations A, B, to convey the severed candy stick to the forming station E and against the stop 112. Inasmuch as the forming station E is operating synchronously with the cutter station C, the candy stick S will engage the stop 112 with assurance that there will be no interference to such movement against the stop by a set 152 of forming dogs 133, the latter being to the rear of the candy stick, but in a position to promptly engage it. The moving dogs 133 force the candy sticks between the curved guide rails 139, 139a to produce the cane shape, conveying the cane along the guide rails 138 to insure the straight configuration of the candy leg L,

which is held between a set 152 of dogs and one guide rail 138, while the terminal portion P of the handle is held between the same set of dogs and the other guide rail 138. The conveyor 132 progressively carries the formed candy cane S to the discharge end of the counter 111, where it normally passes through a cooling tunnel (not shown), to enable it to harden from its semi-plastic state.

It is apparent that a twisted candy cane forming apparatus has been provided which is capable of sizing the candy, effecting its twisting, its severing into proper lengths, and its forming into the candy cane all in an automatic manner. The mechanism can be operated very rapidly and economically, there being a minimum of waste of materials as a result of its operation. In addition, its speed of operation can be varied, as by varying the effective diameters of the variable speed pulley 22 of the drive motor 20, which rotates the elements 14, 15 of the sizer station A, and the elements 54, 55 of the twister station B, and by adjusting the variable pulley or pulleys 90, 93 mounted on the other motor shaft 91 and the gear reducer shaft 94, and through which motion is transmitted to the cutter station C and the forming station E.

The inventor claims:

1. In candy forming apparatus: movable cutter means for severing candy in elongate form into individual sticks; opposed spaced forming members having an entry opening therebetween; stop means adjacent said opening for locating an end axial portion of a candy stick across said opening transversely of said members and in a position to engage said members; means for feeding the candy in elongate form to the cutter means at a predetermined speed; means for conveying each stick from said cutter means at a substantially greater speed than said predetermined speed to and against said stop means and across said entry opening; and means movable transversely of and engageable with the end axial portion of each stick for forcing the stick through said opening against and between said members to form each stick into a cane.

2. In candy cane forming apparatus: cutter means for severing candy in elongate form into individual sticks; opposed spaced forming members having an entry opening therebetween; means adjacent said opening for locating an end axial portion of a candy stick across said opening transversely of said members and in a position to engage said members; means for feeding the candy in elongate form to the cutter means at a predetermined speed; means for conveying each stick from said cutter means at a substantially greater speed than said predetermined speed to and against said locating means and across said entry opening; and means engageable with each stick for forcing the stick through said opening against and between said members to form each stick into a cane.

3. In candy cane forming apparatus: cutter means for severing candy in elongate form into individual sticks; opposed spaced forming members having an entry opening therebetween; means adjacent said opening for locating an axial end portion of individual sticks across said opening; means for feeding the candy in elongate form to the cutter means at a predetermined speed; means for conveying each stick from said cutter means at a substantially greater speed than said predetermined speed to and against said locating means and across said entry opening; a conveyor adjacent said forming members and having forming dogs secured thereto at intervals along its length, said dogs being movable into said opening and between said forming members, said dogs being successively engageable with the sticks for forcing the sticks against and between said members to form each stick into a cane and to convey each stick along said member; and means for moving said conveyor.

4. In candy forming apparatus: movable cutter means for severing candy in elongate form into individual sticks; opposed spaced forming members having an entry opening therebetween; stop means adjacent said opening for locating an end axial portion of a candy stick across said opening transversely of said members and in a position to engage said members; means for feeding the candy in elongate form to the cutter means at a predetermined speed; means for conveying each stick from said cutter means at a substantially greater speed than said predetermined speed to and against said stop means and across said entry opening; means engageable with the end axial portion of each stick for forcing the stick through said opening against and between said members to form each stick into a cane; and means for moving said cutter means and forcing means in synchronism with each other.
5. In candy forming apparatus: movable cutter means for severing candy in elongate form into individual sticks; opposed spaced forming members having an entry opening therebetween; stop means adjacent said opening for locating an end axial portion of a candy stick across said opening transversely of said members and in a position to engage said members; means for feeding the candy in elongate form to the cutter means at a predetermined speed; means for conveying each stick from said cutter means at a substantially greater speed than said predetermined speed to and against said stop means and across said entry opening; means engageable with the end axial portion of each stick for forcing the stick through said opening against and between said members to form each stick into a cane; and means for moving said cutter means and forcing means in synchronism with each other.
6. In candy cane forming apparatus: cutter means for severing candy in elongate form into individual sticks; a supporting structure; opposed spaced forming members on said structure having an entry opening therebetween; means adjacent said opening for locating an end axial portion of a candy stick on said structure across said opening and transversely of said members and in a position to engage said members; means for feeding the candy in elongate form to the cutter means at a predetermined speed; means for conveying each stick from said cutter means at a substantially greater speed than said predetermined speed to and against said locating means and across said entry opening; means engageable with the end axial portion of each stick for forcing the stick through said opening against and between said members to form each stick into a cane; and means for moving said cutter means and forcing means in synchronism with each other.
7. In candy cane forming apparatus: cutter means for severing candy in elongate form into individual sticks; a supporting structure having two spaced apart side portions; opposed spaced forming members on said portions having an entry opening therebetween; means adjacent said opening for locating an axial end portion of individual candy sticks on said portions across said openings; means for feeding the candy in elongate form to the cutter means at a predetermined speed; means for conveying each stick from said cutter means at a substantially greater speed than said predetermined speed to and against said locating means and across said entry opening; a conveyor adjacent said forming members and having forming dogs secured thereto at intervals along its length and movable into said opening and between said forming members, said dogs being successively engageable with the sticks for forcing the sticks against and between said members to form each stick into a cane and to convey each stick along said members; and means for moving said cutter means and conveyor in synchronism with each other.
